CLAIM

The ornamental design for a container assembly, as shown
and described.

DESCRIPTION

FIG. 1 is a top perspective view of a container assembly
showing our new design;

FIG. 2 is a front elevation thereof;

FIG. 3 is a rear elevation thereof;

FIG. 4 is a first side view thereof;

FIG. 5 is a second side view thereof;

FIG. 6 is a top plan view thereof; and,

FIG. 7 is a bottom plan view thereof.

The broken lines in the drawings illustrate portions of the
container assembly that form no part of the claimed design.
The dot-dash broken lines illustrate a symbolic break in
height and form no part of the claimed design.

1 Claim, 4 Drawing Sheets
